UNITED STATES PATENT OFFICE.

JAMES D. STOAKES, OF DETROIT, MICHIGAN, ASSIGNOR, BY DIRECT AND MESNE ASSIGNMENTS, OF ONE-HALF TO C. P. CHAMBERLIN, OF DETROIT, MICHIGAN, AND ONE-HALF TO JOSEPH N. SMITH & COMPANY, OF DETROIT, MICHIGAN, A CORPORATION OF MICHIGAN.

HINGE.

1,100,684.

Specification of Letters Patent. Patented June 16, 1914.

Application filed January 27, 1913. Serial No. 744,449.

To all whom it may concern:

Be it known that I, JAMES D. STOAKES, a citizen of the United States of America, residing at Detroit, in the county of Wayne 5 and State of Michigan, have invented certain new and useful Improvements in Hinges, of which the following is a specification, reference being had therein to the accompanying drawings.

10 The invention relates to hinges and has among the objects thereof to provide a construction of concealed hinge which will permit of varying movements of the inner edge of the door at the points where the hinges 15 are secured, but will nevertheless effect a movement of the top and bottom edges of the door in substantially, horizontal planes; and further to provide such a hinge that is exceedingly compact when closed.

20 Other objects of the invention will more fully hereinafter appear.

The invention resides in the novel construction, arrangement and combination of parts as herein described and claimed.

25 As my improved construction of hinge is particularly adapted to automobiles, I will illustrate and describe the same as applied to the door of a motor vehicle.

In the drawings, Figure 1 is a fragmentary, perspective view of an automobile body and door, with my improved construction of hinge applied thereto; Fig. 2 is a similar view of the hinge open; Fig. 3 is a view looking in the opposite direction from 35 Fig. 2; Fig. 4 is a view of the hinge closed; and Fig. 5 is a section on the line $x-x$ of Fig. 4.

A designates the door of an automobile and B the casing.

40 C and D are the hinges connecting the door and casing. In the usual construction of automobile body the body side and door are curved inward adjacent the bottom. Therefore, in order for the top and bottom edges of the door to swing in horizontal planes the hinge D must provide for a greater movement than the hinge C. With my improved construction this may be readily accomplished by merely increasing 45 the length of the hinge leaves, as will more fully hereinafter appear.

As shown, the hinge C is composed of plates E and complementary leaves F G, the leaves each having eyes H at their outer

ends adapted to aline with knuckles I on the 55 leaves and pivotally connected thereto by a pin J. The inner ends of the leaves also are provided with inter-engaging knuckles K and L pivotally connected by a pintle M. The pivot pins J are positioned at an angle 60 to the axis about which the door turns, while the pintle M is transverse to the pivot pins. By so arranging the pivot pins and the pintle the door is caused to swing in an arc, though the vertical axis about which the 65 door turns shifts laterally during movement of the door and the top and bottom edges of the door are maintained in horizontal planes. That is, the hinges prevent sagging 70 of the door in the opening movement of the latter. When the hinge is closed the pintle is at an angle to the pivot pins, as shown in Figs. 4 and 5, making the hinge parts readily responsive to but a slight stress in opening the door.

75 It will be noted upon reference to Figs. 2 and 3 that the knuckles I of the plates are off-set toward the inner sides of the latter, providing flat outer faces N for engaging the edges of the door and casing, while the 80 eyes H and the knuckles K and L are so positioned as to permit the faces O of the leaves to lie flat against the inner sides P of the plates and to allow the opposite faces Q of the leaves to abut when the hinge is 85 closed. Preferably the plates are provided with flanges R which form therewith a housing for receiving the leaves.

In applying the hinge to the door and casing the adjacent edges S T thereof are recessed as indicated at U to receive the plates. The latter are then secured in place by suitable screws V passing through apertures W in the plates and when the hinge is attached the outer edges of the flanges lie in the plane 95 of the door or casing edge to which it is secured. By this arrangement it is merely necessary to recess the edges of the door and body to a depth equal to the height of the flanges R. Preferably the ends as X of the 100 recesses for one of the hinges are positioned to form stops for the leaves during opening of the door so as to prevent the leaves from passing into the plane of the pivot pins. This avoids the pivot pins and 105 pintle from reaching dead center, so to speak.

As before stated, the hinge D must pro-

vide for a greater movement than the hinge C. This is accomplished by increasing the length of the leaves. The relation of the pivot pins and pintle however, remain the same. In order to provide housings for the leaves it is of course, necessary to proportion the length of the plates to correspond to the increase in the length of the leaves.

What I claim as my invention is:

10 1. A hinge, comprising plates and complementary leaves pivoted together at their inner ends and pivotally connected to the plates at their outer ends at an angle to the longitudinal axis about which the plates move relative to each other, the inner ends of the leaves being arranged intermediate the opposite ends of the plates.

20 2. A hinge, comprising plates and complementary leaves pivotally connected to the plates at their outer ends and pivoted together at their inner ends, the axis of the last-mentioned pivot being at an angle to the longitudinal axis about which the plates move relative to each other, the inner ends of the leaves being arranged intermediate the opposite ends of the plates.

30 3. A hinge, comprising plates and complementary leaves pivotally connected to the plates at their outer ends at an angle to the longitudinal axis about which the plates move relative to each other, said leaves being pivoted together at their inner ends, the axis of the last-mentioned pivot being transverse to said longitudinal axis, the inner ends of the leaves being arranged intermediate the opposite ends of the plates.

35 4. A hinge, comprising plates and complementary leaves pivotally connected to the plates at their outer ends at an angle to the

longitudinal axis about which the plates move relative to each other, said leaves being pivoted together at their inner ends, the axis of the last-mentioned pivot being transverse to said longitudinal axis and also transverse to the pivotal connections between the plates and the leaves, the inner ends of the leaves being arranged intermediate the opposite ends of the plates.

5. A hinge, comprising plates and complementary leaves pivoted at their outer ends to the plates, each pivotal connection between the leaf and its corresponding plate being off-set inward from the outer face of the plate, said leaves being pivoted together at their inner ends, each of said pivotal connections being at an angle to the longitudinal axis about which the plates move relative to each other.

6. A hinge, comprising plates and complementary leaves pivoted together at their inner ends and pivotally connected to the plates at their outer ends, the pivotal connection between each leaf and its corresponding plate being off-set inward from the outer face of the plate and each of the latter having a flange extending there-around coöoperating with the plate to form a housing for the leaf in the closed position of the hinge, the pivotal connection being transverse to the longitudinal axis about which the plates move relative to each other.

In testimony whereof I affix my signature in presence of two witnesses.

JAMES D. STOAKES.
